[57] **CLAIM**

The ornamental design for a fishing pole spool holder, as shown and described.

DESCRIPTION

FIG. 1 is a front elevational view of a fishing pole spool holder showing my new design;

FIG. 2 is a rear elevational view thereof;

FIG. 3 is a side elevational view thereof;

FIG. 4 is a top plan view thereof;

FIG. 5 is a bottom plan view thereof; and,

FIG. 6 is a rear elevational view of another embodiment of my spool holder, the front, top and bottom views thereof being the same as in FIGS. 1, 4, and 5.

FIG. 1

FIG. 2

FIG. 3

FIG. 4

FIG. 5

FIG. 6
